UNITED STATES PATENT OFFICE.

ROBERT K. SMITHER, OF BUFFALO, NEW YORK.

OINTMENT-INJECTOR.

SPECIFICATION forming part of Letters Patent No. 627,658, dated June 27, 1899.

Application filed December 5, 1898. Serial No. 698,363. (No model.)

To all whom it may concern:

Be it known that I, ROBERT K. SMITHER, a citizen of the United States, residing at Buffalo, in the county of Erie and State of New York, have invented new and useful Improvements in Suppositors or Ointment-Injectors, of which the following is a specification.

This invention relates to an injector or sup-
10 positor for introducing an ointment or other
medication into the orifices of the body—such,
for instance, as the rectum in the treatment
of piles.

The object of my invention is the provision
15 of an inexpensive instrument of this character
which is readily charged or prepared for
use and by which a predetermined quantity
of the desired medication can be conveniently
injected.

20 In the accompanying drawings, Figure 1 is
a longitudinal sectional elevation of my im-
proved suppositor, showing the plug or fol-
lower and the plunger fully inserted in the
instrument. Fig. 2 is a similar view showing
25 the ointment-chamber of the barrel filled pre-
paratory to inserting the plug and the plun-
ger. Fig. 3 is a similar view showing the
plug inserted and the plunger partly pressed
into the barrel. Fig. 4 is a cross-section on
30 line 4 4, Fig. 1. Figs. 5 and 6 are fragmen-
tary longitudinal sections showing slightly
modified constructions of the instrument.

Like letters of reference refer to like parts
in the several figures.

35 A is a cylindrical tube or barrel forming
the body of the instrument and having a
rounded front end or nozzle to facilitate its
entrance into an orifice of the body. The
bore of the barrel extends from end to end
40 thereof.

C is a bulb or hollow enlargement arranged
at the rear end of the barrel and forming a
chamber adapted to receive the ointment or
medication to be applied to the affected part.

45 The front end of this chamber communicates
with the bore of the barrel A, while its rear
end is open and adapted to receive a plug or
follower D, whereby the ointment placed in
the chamber is forced into the cavity of the

50 barrel. This plug has at its outer end a
flange or rim d, which bears against the rear
end of the ointment-chamber when the plug

is fully inserted therein, as shown in Figs. 1
and 3.

E is a rod or plunger adapted to be inserted 55
in the barrel of the instrument for ejecting
the ointment therefrom and depositing it
upon the part or surface under treatment.
This plunger is of the proper size to snugly
fit the bore of the barrel, and the plug or fol- 60
lower is provided with an opening for the pas-
sage of the plunger, which opening is ar-
ranged in line with the bore of the barrel and
closely fits the plunger. The plunger is pro-
vided at its rear end with a knob or handle 65
and is preferably made of such length that
when the same is pressed into the barrel un-
til the inner end of its knob comes in contact
with the plug D the front end of the plunger
is flush with or projects slightly beyond the 70
nozzle of the barrel, so as to discharge the
entire contents of the latter.

In the use of the suppositor the plug and
the plunger are removed and the desired 75
amount of medication is placed in the oint-
ment-chamber C. The plug is then pressed
fully into the chamber, the plunger-opening
of the plug being at the same time closed by
the finger, thus forcing the entire contents of 80
the chamber, except the ointment which en-
ters the cavity of the plug, into the barrel of
the instrument. The plunger is now passed
through the plug into the barrel and pressed
until the medication appears at the nozzle of 85
the suppositor. The barrel is then inserted
in the orifice or passage of the body to be
treated and the plunger is pressed into the
barrel to its limit, thus expelling the entire
contents of the barrel.

In applying remedies to the rectum, as in 90
the treatment of piles, it is desirable to insert
the suppositor beyond the sphincter before
beginning to discharge the medication and
then gradually withdraw the instrument, at
the same time pressing the plunger into the 95
barrel to deposit the ointment along the sur-
face of the bowel.

By providing the instrument with a cham-
ber independent of the barrel in which the
ointment is placed preliminary to forcing it 100
into the barrel the instrument can be con-
veniently and accurately charged with the
desired predetermined quantity of medica-
tion, and as the chamber can be wholly emp-

tied by the insertion of the plug and the plunger the proper application of the entire contents of the suppositor is insured.

If desired, the barrel may be closed at its front end and provided in its side, near its end, with perforations, as shown in Fig. 5, or with slots, as shown in Fig. 6, whereby the medication is discharged in a lateral direction.

10. I claim as my invention—

A suppositor or injector comprising a barrel provided at one end with a discharge-opening and at its opposite end with a chamber or enlargement for the medication, which 15 chamber is open at its rear end, a removable

plug or follower constructed to fit closely into said chamber and adapted to be inserted therein for forcing the medication from the chamber into said barrel, and a plunger constructed to closely fit the bore of the plug and of the barrel and adapted to be inserted therein behind the material forced into it, for expelling the material therefrom, substantially as set forth.

Witness my hand this 30th day of November, 1898.

ROBERT K. SMITHIER.
